UNITED STATES PATENT OFFICE.

BERTHOLD ZEITSCHEL, OF BERLIN, GERMANY.

REGENERATIVE GAS-LAMP.

SPECIFICATION forming part of Letters Patent No. 430,723, dated June 24, 1890.

Application filed June 12, 1889. Serial No. 814,022. (No model.) Patented in Belgium June 6, 1889, No. 86,542; in Norway June 6, 1889, No. 1,390; in Switzerland June 6, 1889, No. 1,089; in England June 6, 1889, No. 9,412, and in Spain June 6, 1889, No. 9,666.

To all whom it may concern:

Be it known that I, BERTHOLD ZEITSCHEL, a subject of the King of Prussia and German Emperor, and a resident of Berlin, have invented certain new and useful Improvements 5 in Regenerative Gas-Lamps, (for which I have obtained patents in Switzerland, No. 1,089, dated June 6, 1889; in England, No. 9,412, dated June 6, 1889; in Spain, No. 9,666, dated 10 June 6, 1889; in Belgium, No. 86,542, dated June 6, 1889; in Norway, No. 1,390, dated June 6, 1889, and for which I have filed applications in Germany, May 25, 1889; in Austria-Hungary on June 6, 1889, and in Russia 15 May 25, 1889,) of which the following is an exact description.

My invention relates to an improved construction of lamps having two circular burners, the manner of the burners and air-inlet 20 co-operating to avoid the formation of smoke-black, thus effecting a more thorough combustion of the gas.

In order to make my invention more clear, I refer to the accompanying drawings, in 25 which similar letters denote similar parts throughout the different views.

Figure 1 is a vertical section through the middle of the lamp. Fig. 2 is a horizontal section through the lamp along the line $\alpha \beta$ 30 in Fig. 1.

The gas is led by means of supply-pipe p into the chamber n , formed by cover x , screwed into the under part x' . Into this under piece x' are fixed tubes $a a$ and $b b$, constituting 35 the outer and inner burners. This chamber n is screwed onto the cast piece y , adapted to form the various passages s', s^2, s^3 , and s^4 for the air-circulation. The form of the cast piece y will be clearly seen in Fig. 2. To the lower part of piece y is attached ring b' , encircling the outer burner b . To the under side of the bottom of chamber n is fixed cylinder y' , having holes $s s$, and to the lower end of which ring a' is fixed, encircling the 45 inner burner a .

The cast piece y , which serves to regulate the air-circulation, is screwed into ring x' , to which cap x^2 is also attached. The frame R ,

for holding glass r' , is hinged to ring x' , which also contains sheet-metal ring x^3 . The sheet-metal cap or shade x^4 is suspended on the cast piece y . The sheet-metal cap x^2 , together with ring x^3 and shade x^4 , causes the air to circulate to the burners in a zigzag manner, whereby the same is more thoroughly warmed. 50 To the top part of piece y is fixed the chimney c of the lamp.

The air enters the lamp through the openings $h h$ in ring x' , passes then over ring x^3 60 and under ring-shade x^4 through the passages $s' s^2 s^3 s^4$ in the cast piece y , from whence a part of the air passes downward between the rings a' and b' for supplying the outer ring-burner, while a part passes on through the holes $s s$ in piece y' downward inside the tube a' in order to supply the burner a . As will be seen, the air then passes in the direction of the arrows through the canals $z z$ in the cast piece y and up the chimney. 70

The advantage of a lamp of this construction is that by means of the two circular flames burning one within the other, as shown and described, the air being led to the burners will be compressed to a certain extent, or 75 rather retained between the lines of circumference of the inner and outer flames, and again between the outer flame and lower edge of ring b' , so that only as much air as is necessary for the complete combustion of the 80 gas will circulate, and thus the formation of smoke-black in the lamp will be prevented. On the other hand, by a too-rapid circulation of the air the combustion of the gas is imperfect, burns extravagantly, creating smoke-black, and thereby stopping up the flues or 85 air-passages and causing them to become smaller, and the lamp will in consequence burn badly after having been in use a short time. 90

Having now particularly described my invention, what I claim is—

In regenerative gas-lamps, the combination of the inner circle of tubes $a a a$, outer circle $b b b$, both ending in and receiving their gas- 95 supply from chamber n , having supply-pipe

p, piece x^2 , with cover x , ring x' , having air-inlets h h h , piece y , having air-inlets s' s' , cylinders y , having air-inlets s s , cylinders a' and b' , sheet-metal ring x^3 , shade x^4 , cap x^5 , chimney c , and glass ring and glass r' , in the manner and for the purpose substantially as described.

In witness whereof I have hereunto set my hand in presence of two witnesses.

BERTHOLD ZEITSCHEL.
